Primary Examiner—Ted Shooman*Assistant Examiner*—Richelle Shelton**[57] CLAIM**

The ornamental design for a "retractable tethered ball baseball practice device", as shown and described.

DESCRIPTION

FIG. 1 is a top, front and right side perspective view of a retractable tethered ball baseball practice device showing my new design, the top, rear and right side perspective view being a mirror image;

FIG. 2 is a left side view thereof;

FIG. 3 is an enlarged and fragmented top plan view thereof; and,

FIG. 4 is an enlarged and fragmented bottom plan view thereof.

FIGS. 3 and 4 are shown fragmented for ease of illustration.
